APPARATUS FOR TRUING UP TUBULAR BODIES

Chalmer E. Murphy, Cleveland Heights, Ohio, assignor to Porcelain Steels, Inc., Cleveland, Ohio, a corporation of Ohio

Application November 25, 1940, Serial No. 367,077

6 Claims. (Cl. 153—80)

This invention relates to metal-working machines and methods.

While my invention has other uses it is particularly applicable to the process of making enamel-coated tanks, illustrative of which is the domestic hot water supply tank and my invention will be illustrated and described herein as applied to that use. A construction of hot water tank is illustrated and described in co-pending applications filed by me and to be referred to hereinafter and this construction will therefor herein be briefly described. The tank comprises a cylindrical tubular body of sheet steel to the opposite ends of which heads are attached. The body and the heads are coated inside or outside and outside with vitreous enamel, that is to say, with enamel fired and fused from dried enamel slip; and the heads are attached in sealed relation to the body after enameling.

Such tanks in use contain hot water under pressure and at the time of manufacturing them the manufacturer must test them under much greater internal pressure to be able to guarantee for them long useful leak-proof and pressure-proof life. The enamel coat is glass-like and brittle. Any deformation of or bending of the metal of the walls of the tank after assembling, such as might be caused by the applied internal pressure in use, will crack the enamel. The main purpose of the enamel coat is to prevent contact of the hot water in the tank with the metal of the wall which as is well-known corrodes the wall, and in a relatively short period of time perforates the wall and produces a leak which ends the useful life of the tank; and if a crack develops in the inside enamel coat it will expose the metal of the wall to the corrosive action.

Pressure in the tank may deform the walls of the tank and crack the enamel in several ways. If the heads are not semi-spherical in form, pressure will deform them toward more nearly true spherical form. Spherical heads are not desirable nor acceptable commercially, the preferred form of head being hemi-ellipsoidal in cross-section; and pressure deformation of the head can be acceptably and economically prevented by making the heads of sufficiently thick material. But to make the main cylindrical body of the tank of such thick metal would raise the cost of the tank to a commercially prohibitive figure. The body therefor must be made of relatively thin metal and if there are any flat or planar portions thereon, or if it is out of true cylindrical form to a considerable degree, or if there are any

curved portions which tend to be straightened out by the longitudinal forces thereon exerted by the internal pressure on the opposite heads, such portions will deform or bend and crack the enamel.

Also when high test pressure is used and the body wall is bent, the portions of the body midway between the heads bends or bulges outwardly, relative to portions more nearly adjacent the heads and this cracks the enamel.

If the heads are attached to the body ends before enameling, making of the tank a closed container, difficulties are encountered in obtaining a complete and solid coat of enamel because free circulation of oxygen-containing air over the surfaces while the slip is being dried and while the dried slip is being formed is prevented. For this reason I prefer to form the body and the heads separately and enamel them separately and then attach the heads to the body. Also by making the heads and body separately they may be completely inspected before enameling and any roughnesses on the surfaces can be removed before enameling. The preferred means for attaching the heads comprises the use of a circular series of bolt devices and it is therefor desirable when making the bodies in quantities independently of the heads, for the bodies to be substantially of uniform diameter.

30 The present invention relates more particularly to a machine and method for truing up the body before enameling it to make it of circular cross section; and to remove any planar or out of round portions which might be deformed and cause cracking of the enamel by internal pressure; and to remove unequal strains in the metal which might cause the body wall to be deformed when heated during the enameling process.

The invention comprises means to mechanically expand the tubular body wall on all diameters equally over its entire length and including, if preferred, the metal head-attaching rings and the flanges referred to above, to true the same, and sufficiently to set the metal in its expanded condition, and to attain a predetermined diameter of all of a number of like bodies to render them readily assemblable and interchangeable with the heads.

It is among the objects of the invention therefor,

To provide an improved hot-water tank body construction worked in an improved manner to retain unbroken a coat of vitreous enamel when subjected to internal pressure in use.

To provide an improved machine and method

for working the metal wall of the tubular tank body to cause it to retain its form and not to be deformed by internal pressure therein so that an enamel coat thereon will not be cracked by the pressure.

To provide an improved method and means for working the metal of a metal head-attaching ring at the end of a tubular tank body and/or a flange formed over the ring.

To provide an improved machine and method for making the tubular metal body wall of a hot water or like tank having means for attaching heads to the ends thereof.

Other objects will be apparent to those skilled in the art to which my invention appertains.

My invention is fully disclosed in the following description taken in connection with the accompanying drawings in which,

Fig. 1 is a view with parts broken away of a tank to the making of the parts of which the machine and method embodying my invention may be applied;

Fig. 2 is a fragmentary longitudinal sectional view to enlarged scale of a part of the tank of Fig. 1 illustrating one means for attaching the heads thereof to the body thereof;

Fig. 3 is a view in longitudinal section, with parts broken away, of the body of the tank of Fig. 1, and illustrating a part of the method of making it;

Fig. 4 is a view in longitudinal section and in some respects diagrammatic, illustrating a machine by which a metal working operation may be performed on a tank body such as that shown in Figs. 2 and 3;

Fig. 5 is a cross-sectional view taken from the plane 5—5 of Fig. 4;

Fig. 6 and Fig. 7 are fragmentary views similar to corresponding parts of Fig. 4 illustrating modifications.

In Figs. 1 to 3 of the drawings, a tank is illustrated comprising a tubular cylindrical body 1, and upper and lower heads 2 and 3. Any desired number of conduits 4—4 may be provided for communication with the interior of the tank, and, if desired, conduits not shown may be provided communicating with the tank interior through the wall of the body 1.

The preferred construction of the body 1, is shown in Figs. 2 and 3, and comprises metal rings 5—5 surrounding the body, inwardly of its ends, and flanges 6—6 bent outwardly and coined over the rings 5, the end portions of the wall being shown in dotted line at 6A before the flanges are formed.

The body in the first instance, and before the flanges 6 are formed, or the rings 5 applied, may be made by rolling a sheet of metal into generally tubular form and welding abutting edges thereof together along a seam indicated at 7, which seam is preferably performed by the flash welding process and the flash fin tooled off down to the solid metal to facilitate the forming of an enamel coat thereover.

The metal of the body 1, is then worked by the machine and method of this application to be presently described, and the rings and flanges being provided either before or after this metal working operation is performed, as shown in Fig. 2, a coat of vitreous enamel 8 is formed preferably both on the inside and outside and over the flange 6 and ring 5. The heads, such as the head 2 of Fig. 2, are then mounted on the ends of the body. Preferably these heads comprise an annular planar portion 9 opposite the flange 6,

and a skirt 10 radially outwardly of the flange 6 and ring 5, and coated with vitreous enamel 11 covering the head, the planar portion and the skirt.

In the space between the skirt 10 and the ring 5 and flange 6, bolts 12 are projected downwardly, through suitable perforations in the head and threaded through plates or washers 13 bridging the skirt periphery and ring 5, to exert a clamping action upon a sealing gasket 14 between the head and the flange 6 to effect a liquid-tight and pressure-proof seal therat.

Another construction for attaching the heads to such a body is shown in my pending application Serial Number 339,753 filed June 10, 1940, for improvements in Enamelled hot water tanks and involving a flange and a ring as referred to above.

In the forming the body 1 and in applying the ring 5, for example by tack or spot welding it to the body, and in forming the flange 6, these parts may become out of round transversely; and particularly the body wall 1 may have relatively flat portions thereon; and even if they were carefully made so as to be circular in cross-section, there may be strains in the metal which, when the metal is heated to form the enamel coat, would cause these parts to go out of round or to assume relatively flat shape in portions thereof. A machine and method will now be described by which these irregularities may be removed not only in intermediate portions of the body longitudinally, but also in the rings and flanges if desired. This machine and method not only removes these irregularities which might result in cracking of the enamel when the finished tank is subjected to internal pressure as referred to, but, as the result of causing a quantity of such bodies to be all of substantially the same diameter and circular form, the attachment of the heads is facilitated and makes separately made bodies interchangeable with separately made heads.

Referring to Figs. 4 and 5 I have shown at 15 a main frame or base having in the upper portion thereof an inwardly extending flange 16 providing 45 a large opening 17. A plurality of angularly spaced radial grooves 18—18 are provided in the upper part of the flange 16.

An expanding tool or mandrel is provided in the upper central part of the machine and comprises 50 a plurality of upwardly elongated expanders 19—19 disposed in a cylindrical series around a vertical axis the radially outer portions 20—20 thereof defining substantially a cylinder. At their lower ends the expanders 19 have outwardly 55 radially extending feet 21—21 thereon, arranged to rest in and be supported in and to slide radially in the grooves 18. The feet 21 are provided with radial slots 49 through which bolts 48 are loosely projected and threaded into the flange 16 to hold the expanders upright, but permitting them to move radially.

The outward radial movement of the feet 21 in the grooves 18, and therefore of the lower ends of the expanders 19—19, is limited and stopped by their engagement with the ends 22 of the grooves. Correspondingly the outward radial movement of the upper ends of the expanders 19—19 is stopped by a ring 23 resting and floating upon shoulders 24—24 on the upper ends of the expanders, the shoulders being formed by notches therein, the side walls 25—25 of the notches being engageable with the ring.

The expanders 19—19 normally are moved to and held in their radially inner positions illustrated, by springs 26—26 abutting at their inner

ends upon the feet 21—21 and abutting at their outer ends upon the main frame or base, the main frame for this purpose extending upwardly as at 27 beyond the grooves 18 and having recesses 28 to receive the springs.

On the upper and lower inner confronting portions of the expanders 19—19 they are provided respectively with inclined preferably conical faces 29—29 and 30—30 as shown in Fig. 4. An upper expanding cone 31 is projected downwardly into the cylindrical series of expanders 19—19, and engages the faces 29, and a lower expanding cone 32 similarly engages the faces 30.

The upper cone 31 is connected by means of a piston rod 33 with a piston 34 in a fluid pressure cylinder 25, the piston rod 33 extending through the lower cone 32. The lower cone 32 is connected to the wall of the cylinder 35 preferably by means of an annular flange 36 on the lower cone bolted to the cylinder.

The cylinder 35 may rest upon a support 37 on the lower part of the frame in its normal or unactuated position.

The piston rod 33 passing through the cone 32 may be sealed against escape of pressure from the cylinder 35 by a packing gland construction 38.

Conduit connections 38 and 39 are provided to introduce fluid pressure to the cylinder 35 above or below the piston 34 and to exhaust it from below or above the piston respectively. As shown diagrammatically the conduits 38 and 39 lead to a valve device 40 having connected thereto a pressure supply line 41 and an exhaust line 42.

The construction of this valve constitutes no essential parts of the present invention and may be any well-known valve for the purpose. The valve diagrammatically shown comprises a handle 43, and upon moving the handle in one direction, say toward the right, fluid pressure is admitted from the supply line 41 to the conduit 38 supplying pressure above the piston 34 and exhausting pressure from below the piston and out by the conduit 39 to the exhaust 42; and upon moving the handle in the other direction pressure above the piston is exhausted and pressure below the piston is applied to the cylinder 35.

The tank body comprising the body 1 the rings 5 and the flanges 6 is shown in Fig. 4 telescoped over the expanders 19 in position to be worked as described above, and for this purpose the flange 6 may rest upon the feet 21.

In order that the expander may work bodies of different lengths, the expanders 19 are made long enough to extent somewhat over one-half of the length of the longest body to be worked.

In the operation thus far described, the valve 43 is moved to cause the piston 34 to move upwardly and raise the cone 31 and to cause the cylinder 35 to move downwardly and lower the cone 32. The springs 26 move the expanders 19—19 inwardly to engage the cones.

The body is then telescoped downwardly over the expanders 19 into the position illustrated. The ring 23 at all times is inwardly of and clears the inner wall of the body 1. The valve handle 43 is then moved to admit pressure to the upper side of the piston cylinder 34, the pressure acting to move the piston and the cone 31 downwardly and the cylinder 35 and the cone 32 upwardly. The cones 31 and 32 reacting upon the inclined faces 29 and 30 expand the expanders 19—19 radially outwardly and this goes on until the feet 21 engage and are stopped upon the ends 22 of the grooves 18, and until the notch walls 25 engage the ring 23 beyond which positions the

expanders as will be apparent cannot be moved.

After the operation thus performed is completed, the valve handle 43 is moved to exhaust pressure from above the piston 34 and to apply pressure below it which moves the cone 31 upwardly and the cone 32 downwardly to relieve the expanding pressure from the expanders 19—19 and they are returned to their normal positions by the springs 26.

When the cones 31 and 32 are moved as described to exert their expanding pressure, one of them may move first followed by movement of the other; and similarly when the fluid pressure is released to return them one of the cones may move before the other. In some cases when the pressure between the cones and the expanders 19 is released, the cylinder 35 may be suddenly projected downwardly and its downward movement will be stopped on the support 37. In other cases, the cone 31 may jump upwardly with a quick movement, and to limit this movement, a plate 44 may be provided resting loosely on the upper end of the cone 31 and having bolts 45 embraced by slots 46, and the plate will strike upon the heads of the bolts, and stop movement of the cones 31, the bolts being screwed into the upper ends of the expanders 19—19. If the cone is pulled inwardly beyond the ends of the expanders, the plate 44 will be deposited on the ends of the expanders. Similarly at the time of such quick movement, the expanders 19 may tend to move inwardly with a quick or jumping movement, but they are stabilized by the bolts 48.

After one-half or more of the body has thus been worked, and after the pressure has been removed, the body is withdrawn from the expanders 19 and turned end for end and the operation repeated on the other half portion.

The outer diameter 20 of the assembly of expanders 19—19 is such that the body 1 will telescope thereover with suitable clearance for a body 1 of approximate pre-selected diameter attained in the making of the body; and the extent of movement permitted by the expanders 19 in moving to their definitely stopped positions as described above, is pre-determined to expand the body wall, rings 5, and flanges 6, a predetermined amount. This amount is pre-determined to be sufficient to stretch the metal of the wall slightly beyond its elastic limit and therefor to set the metal in its stretched condition so that the worked and stretched body is made permanently of larger diameter than when originally made. Besides this as will be obvious it is rendered substantially circular in cross-section at all parts and to this latter end, the surfaces of the expanders 19 which engage the inner wall of the body may be so formed that the cylinder 20 defined thereby is a true cylinder after the radially outward movement of the expanders 19—19 has taken place. Thus any planar portions or out of round portions of the body ring or flange are removed by this metal-working operation.

The stretching of the metal beyond its elastic limit also precludes any possibility that internal pressure even a high-testing pressure will further expand the body and crack an enamel coat thereon during testing, the thickness of the metal of the wall of the body 1 being pre-selected to have a strength to resist expansion beyond its stretched condition by any testing pressure employed; this being desirable because the ends of the body are reinforced by the flanges 6 and rings 5, the longitudinally central part of the wall therefore being the weakest and most liable to

bulge outwardly under internal pressure and crack an enamel coat thereon. When the body is longer than the expanders and as shown in Fig. 4, and if the maximum amount of stretch in the body wall is to be effected, it may be desirable to relieve or taper off the upper ends of the expanders as indicated in dotted line at 50 to avoid producing a shoulder in the body wall, which may not all be removable by the stretching operation on the other end portion of the body when it is reversed on the expanders.

In Fig. 4 I have illustrated and described above a means for stopping and limiting the outward expanding movement of the expanders 19-19. In Figs. 6 and 7 I have shown another means for this purpose which is adjustable. In Fig. 7, a plurality of metal washers 51-51 in the nature of shims are telescoped over the lower cone 32 and rest upon the cone flange 36. When the cone 32 moves upwardly in the expanding direction, these shims engage the lower ends of the expanders 19 and positively stop further movement of the cone. In Fig. 6, the upper cone 31, in this case 31a, is made longer and a plurality of plates or shims 52-52 are placed upon the upper end of the cone secured thereon between the cone and a heavy plate 53 by bolts 54. When the upper cone 31a moves downwardly the plates 52 are stopped upon the upper ends of the expanders 19-19. By changing the number or thickness of the shims 51 and/or 52 the expansion movement of the expanders 19-19 will be definitely stopped by positively stopping the movement of the cones thereby.

Figs. 6 and 7 also illustrate that the body wall 1 to be expanded may have this operation performed on it before the rings 5 and flanges 6 have been provided thereon; and also illustrate that the expanders 19-19 may be long enough to stretch the entire body from end to end at one operation.

It is after the body has been operated upon as described that it is enamel coated as referred to and as indicated in Fig. 3, the purpose of the metal-working operation described being as referred to above to insure against enamel cracking in the finished tank and to facilitate the attaching of the heads and to render a number of bodies interchangeable with a number of heads whereby economies of manufacture may be enjoyed.

As illustrative of the quantitative expansion which may with advantages be utilized, if it be desired to make a tank the diameter of which is 12 inches, it may initially be made of approximately a diameter of 11 $\frac{3}{4}$ inches and then expanded $\frac{1}{4}$ inch on the diameter to bring it up to the 12 inches. An incidental economy is effected thereby. The original body will in circumference be approximately $\frac{1}{8}$ of an inch less in circumference than the finished body and therefore a sheet of steel $\frac{1}{8}$ of an inch narrower may be used in making it. While this is a small saving of material on each tank, when such tanks are made in large quantities the saving is appreciable.

In the machine as illustrated and described above, it will be observed that no lateral guides are provided for either the cone 31 or the cone 32 or the piston and cylinder 34-35, these parts being free to float laterally during operation; and likewise the expanders 19-19 are free to float laterally. By this means the pressure exerted by all of the expanders 19 on the wall of the body will be equalized, each expander 19

exerting the same stretching pressure on the wall as each of the others. It will be observed also that the body being worked, floats on the machine, being free to move laterally so that it is at all times aligned co-axially with the expanders. Which further insures that all parts of the wall of the body will be equally stretched.

My invention is not limited to the exact details of construction of the machine above-described or of the steps of the method which it performs. Changes and modifications may be made within the spirit of my invention without sacrificing its advantages and my invention is comprehensive of all such changes and modifications which come within the scope of the appended claims.

I claim:

1. In a machine for working the metal of a tubular metal body, a main frame; a plurality of radially extending guide ways on the frame; a plurality of parallel, elongated expander elements disposed in a cylindrical series around an axis and having feet respectively slideable in the guide ways; springs yieldingly constraining the feet and their associated expander elements to move toward the axis; the expander elements having faces defining a cylindrical surface; cone elements projected axially into the series of expander elements at each end thereof; means to force the cone elements into the series of expander elements to move them outwardly radially, comprising a cylinder connected to one cone element and a piston in the cylinder and a piston rod connected to the other cone element and extending to the piston through the one cone element; means to communicate fluid pressure to the cylinder on one side of the piston to move the cone elements toward each other to spread the expander elements apart, and to communicate fluid pressure to the other side of the piston to move the cone elements toward each other to relieve the force from the expander elements.

2. In a machine for working the metal of a tubular tank body, a main frame; a plurality of radially extending guide ways on the frame; a plurality of parallel, elongated expander elements disposed in a cylindrical series around an axis and having feet respectively slideable in the guide ways; springs yieldingly constraining the feet and their associated expander elements to move toward the axis; the expander elements having faces defining a cylindrical surface; cone elements projected axially into the series of expander elements at each end thereof; means to force the cone elements into the series of expander elements to move them outwardly radially, comprising a cylinder connected to one cone element and a piston in the cylinder connected to the other cone element; means to communicate fluid pressure to the cylinder on one side of the piston to move the cone elements toward each other to spread the expander elements apart, and to communicate fluid pressure to the other side of the piston to move the cone elements toward each other to relieve the force from the expander elements; and the expander elements being free to move radially independently of each other and floatingly supporting the cone elements, and the cone elements floatingly supporting the piston and cylinder.

3. In a machine for working the metal of a tubular metal body, a main frame; a plurality of radially extending guide ways on the frame; a plurality of parallel, elongated expander ele-

ments disposed in a cylindrical series around an axis and having feet respectively slideable in the guide ways; springs yieldingly constraining the feet and their associated expander elements to move toward the axis; the expander elements having faces defining a cylindrical surface; cone elements projected axially into the series of expander elements at each end thereof; means to force the cone elements into the series of expander elements to move them outwardly radially, comprising a cylinder connected to one cone element and a piston in the cylinder and a piston rod connected to the other cone element and extending to the piston through the one cone element; means to communicate fluid pressure to the cylinder on one side of the piston to move the cone elements toward each other to spread the expander elements apart, and to communicate fluid pressure to the other side of the piston to move the cone elements toward each other to relieve the force from the expander elements; and means to limit outward expanding movement of the expander elements.

4. In a machine for expanding and truing up to cylindrical form the metal of a tubular metal body; a frame; a plurality of elongated expander elements disposed in a generally cylindrical series around an axis, and having outer surfaces defining a cylinder, disposed for telescoping of the body thereover; means supporting the expander elements on the frame and guiding them for movement radially toward and from the axis, and independently of each other; stop means for limiting radial movement of the expander elements away from the axis; a pair of tapered wedging elements disposed within the opposite ends respectively of the cylindrical series of expander elements, for moving the expander elements away from the axis upon movement of the wedging elements axially in opposite directions; a fluid pressure cylinder and a piston therein for moving the wedging elements; the cylinder being connected to one wedging element, and the piston being connected to the other wedging element by a piston rod passing through the said one wedging element; the wedging elements, upon moving axially, being guided by the radially movable expander elements and being floatingly movable radially therewith, and the piston and cylinder being axially and radially movable with the wedging elements to which they are connected.

5. In a machine for expanding and truing up to cylindrical form the metal of a tubular metal body; a frame; a plurality of elongated expander elements disposed in a generally cylindrical series

- around an axis, and having outer surfaces defining a cylinder, disposed for telescoping of the body thereover; means supporting the expander elements on the frame and guiding them for movement radially toward and from the axis, and independently of each other; stop means for limiting radial movement of the expander elements away from the axis; a pair of tapered wedging elements disposed within the opposite ends respectively of the cylindrical series of expander elements, for moving the expander elements away from the axis upon movement of the wedging elements axially in opposite directions; a fluid pressure cylinder and a piston therein for moving the wedging elements; the cylinder being connected to one wedging element, and the piston being connected to the other wedging element by a piston rod passing through the said one wedging element; the wedging elements, upon moving axially being guided by the radially movable expander elements, and being floatingly movable radially therewith, and the piston and cylinder being axially and radially movable with the wedging elements to which they are connected; said stop means comprising means for limiting the axial movement of the wedging elements.
6. In a machine for expanding and truing up to cylindrical form the metal of a tubular metal body; a frame; a plurality of elongated expander elements disposed in a generally cylindrical series around an axis, and having outer surfaces defining a cylinder, disposed for telescoping of the body thereover; means supporting the expander elements on the frame and guiding them for movement radially toward and from the axis, and independently of each other; stop means for limiting radial movement of the expander elements away from the axis; a pair of tapered wedging elements disposed within the opposite ends respectively of the cylindrical series of expander elements, for moving the expander elements away from the axis upon movement of the wedging elements axially in opposite directions; a fluid pressure cylinder and a piston therein for moving the wedging elements; the cylinder being connected to one wedging element, and the piston being connected to the other wedging element; the wedging elements, upon moving axially being guided by the radially movable expander elements, and being floatingly movable radially therewith, and the piston and cylinder being axially and radially movable with the wedging elements to which they are connected.

CHALMER E. MURPHY.
